UNITED STATES PATENT OFFICE.

JAMES B. PHILLIPS, OF PORTLAND, MAINE.

TROLLEY.

No. 918,696.

Specification of Letters Patent.

Patented April 20, 1909.

Application filed January 18, 1909. Serial No. 472,770.

To all whom it may concern:

Be it known that I, JAMES B. PHILLIPS, of Portland, in the county of Cumberland, State of Maine, have invented certain new and useful Improvements in Trolleys, of which the following is a specification.

My invention relates to overhead trolleys such as are used on the booms of crane derricks, and the object of the invention is to devise a trolley and trolley track suitable to be applied to the under side of the boom, and which will have the maximum strength combined with simplicity and cheapness of construction.

My invention is intended to be used in crane derricks such as are used in handling lumber and for other heavy work.

In carrying out the above objects I construct a trolley with two side plates with a sheave pivoted between them and a pair of trucks pivoted to the outside of each plate preferably at or near the top. These two trucks are made to run on parallel rails supported by brackets secured to the rails in such a manner that the space between the rails is left free for the passage of the trolley.

I illustrate my invention by means of the accompanying drawing in which—

Figure 1 is a side elevation of a trolley and trolley track constructed according to my invention, Fig. 2 is an end elevation of the boom and Fig. 3 is an end elevation of a modified form.

In the drawing, A represents the boom and B B are two parallel rails made preferably of flat bar iron with either square or round edges. These rails are supported in hangers C bolted on the under side of the beam by through bolts c². The rails are preferably put up in lengths butted end to end, the joints being formed at the hangers. The rails are secured to the hanger by resting on a projecting portion of the hanger and are secured by suitable bolts b. The hanger has two arms which are somewhat separated and which are connected to the outside of the rails so that the space between the rails is left substantially clear.

The trolley is composed of a sheave F pivoted between two side plates D the side plates and the sheave constituting a single

block. The plates D preferably hang below the rails and extend above them and at or near the upper outside corner of each plate as here shown is pivoted a truck E by means of a pivot e, these trucks resting on the rails B and being adapted to run thereon. The trucks are grooved to conform to the edge of the rail. The trolley is thus supported upon the four trucks by which it is rolled along the track and it is held laterally by means of the parallel rails.

I have shown here the trolley as made double for convenience in doing certain work, that is, the trolleys are two in number placed end to end and fastened together by a plate d' riveted to each piece but it is evident that the trolley may be made single with one sheave instead of two.

In Fig. 3 I have shown an alternative means of supporting the flat rail. In this figure C' represents the hanger arm which is turned up at c' to form a recess into which the rail sets. The rail being thus supported in the recess formed by the hanger will remain in place if desired without the use of bolts.

A trolley constructed as described will stand great strain, it may be easily constructed and erected. The top and sides of the boom are left free to be trussed and strengthened.

In place of the four supporting trucks shown on each trolley it may be made with a single pair of trucks, one on each plate although the use of two trucks on each side serves to steady the trolley.

I claim;—

The herein described overhead trolley track and trolley consisting of a pair of parallel rails, hangers supporting the same, and a trolley composed of a pair of side plates, a sheave pivoted between the side plates and wheels adapted to run on said rails pivoted to the outside of the side plates.

In witness whereof I have hereunto set my hand this 5th day of January, 1909.

JAMES B. PHILLIPS.
